Boiros et al., U.S. Appl. No. 29/374,806, filed Jun. 10, 2010.

Primary Examiner — Elizabeth J Oswecki(74) *Attorney, Agent, or Firm* — Nixon & Vanderhye P.C.(57) **CLAIM**

The ornamental design for a grip portion for a bottle, as shown and described.

DESCRIPTION

FIG. 1 is a rear, left side perspective view of a grip portion for a bottle according to our new design;

FIG. 2 is a reverse perspective view thereof;

FIG. 3 is a rear view thereof;

FIG. 4 is a top view thereof;

FIG. 5 is a left side view thereof, with the right side view thereof being a mirror image thereof (with the exception of the phantom-line threaded portion on the neck); and,

FIG. 6 is a sectional view taken along lines 6-6 of FIG. 3.

In the drawings, the broken lines showing environment or structure of the bottle in FIGS. 1-6 depict portions of the design that form no part of the claim.
